UNITED STATES PATENT OFFICE.

HENRY W. O'NEILL, OF BROOKLYN, NEW YORK, ASSIGNOR TO WESTERN ELECTRIC COMPANY, INCORPORATED, OF NEW YORK, N. Y., A CORPORATION OF NEW YORK.

SWITCHING DEVICE.

Application filed May 4, 1922. Serial No. 558,491.

This invention relates to switching devices, and particularly to such devices for use in telephone or telegraph systems.

One of the objects of the invention is to improve a switching device of this character, which, when associated with a first and second circuit, operates in response to interrupted vibrations through the first circuit to control the second circuit.

Another object of the invention is to control a plurality of circuits by a common vibrating element.

To attain the objects of this invention a diaphragm, to which a sealed receptacle is suitably fixed, is associated with the poles of a permanent magnet, about which are windings connected to the first circuit. The receptacle is provided with leading-in terminals to which a second circuit is connected. For controlling the continuity of the second circuit, a circuit controller comprising a loose contact member is provided which is contained in the sealed receptacle and loosely engages the leading-in terminals. When a train of vibrations is propagated over the first circuit, the vibrations of the diaphragm will have the effect of causing the loose contact member to be violently agitated, thereby opening the second circuit, which circuit will again be closed when the loose contact member is restored by gravity to its normal position upon the cessation of the vibrations in the first circuit. To insure opening of the second circuit, the loose contact member may be so constructed that during agitation its contacting points vibrate out of phase with each other. By the use of supports having insulated portions for the loose contact member, and by varying the position of the insulated portions in the supports, the vibrating action produced by alternating current in the first circuit may be used to open or close the second circuit, as desired.

To further attain the objects of the invention, a plurality of receptacles, having loose contact members for controlling circuits of different characteristics, may be mounted on the diaphragm.

Other and further features of the invention will be clear from the following detailed description thereof.

The invention is illustrated in the accompanying drawings, in which Fig. 1 shows a sectional view of one form of the switching

device together with a schematic showing of 55 the first and second circuits; Fig. 1^A shows an end view of the means for supporting the receptacle on the diaphragm; Fig. 2 shows an enlarged view of the receptacle and circuit controller shown in Fig. 1; Fig. 2^A 60 shows an end view of one of the apertured members of the receptacle which support the vibrating member; Figs. 3 to 9, inclusive, show modifications of the receptacle and the circuit controller contained in the 65 receptacle; Figs. 4^A, 5^A and 6^A show sectional views at the lines AA, 5^A, 5^A, and CC of Figs. 4 and 6, respectively; Fig. 10 shows an end view of two receptacles and means for supporting them; Fig. 11 shows a plan view of 70 Fig. 10 and circuit connections therefor. Like reference numbers have been used to denote similar parts in all of the figures of the drawings.

Referring now to Fig. 1 and Fig. 1^A, which 75 illustrate one form of the switching device, 5 designates a casing, preferably of insulating material within which is located a semi-circular permanent magnet 6, to the opposite poles of which are secured pole pieces 7, 7, 80 carrying windings 8, 8 and having their pole faces 9, 9 located adjacent the diaphragm 10, which is clamped to the casing 6 by means of a cap 11 of insulating material. Mounted on and suitably fixed to the diaphragm by 85 means of a socket is a tubular sealed receptacle 16, preferably of glass, having a leading-in terminal 17 at each end and a metallic contact member 18 loosely engaging the leading-in terminals. The socket 13 may be spot 90 welded or otherwise suitably fixed at its mid point to the center of the diaphragm. The diaphragm 10 should, of course, be of suitable magnetic material, but the socket for fixing the receptacle to the dia- 95 phragm should be of non-magnetic material. The terminals 17, 17 may be of platinum, or any other material suitable for leading-in terminals for glass. Although the shell 5 and the cap 11 are shown as composed of insulating material in the drawing, it is obvious that either the shell 5, or the cap 11 and the shell 5 may be made up of metal in which case one side of the second circuit could be completed through the socket 13 100 and the diaphragm 10.

Referring to Fig. 2, which shows an enlarged view of the circuit controller of Fig.

1. the loose contact member 18 consists of a metallic cylindrical rod having a pin 14 suitably fixed to each end. The pins 14 may be staked in bores in the ends of the member 18, 5 or the member may be reduced at its ends to form the pins as by a turning operation. For the purpose of supporting the pins 14, apertured members 15, 15 are placed at opposite ends of the receptacle. The apertured 10 members 15 are provided with openings 2, 2 (Fig. 2^A), into which the leading-in terminal 17 is swedged. By looping the leading-in terminal 17, the apertured members 15, 15 are rigidly held in the receptacle 16 when 15 the ends of the receptacle are sealed.

If a train of vibrations is passed through the windings 8, 8 (Fig. 1) the diaphragm will be rapidly vibrated, causing the loose contact member 18 to be agitated, resulting 20 in the opening of the contacts 25, 25. By the use of two serially connected contacts 25, 25 it has been found that the second circuit will be open during the entire time that the diaphragm is in a state of vibration. It has also been found that if a train 25 of vibrations is interrupted by an impulse sender, the loose contact member will function to produce corresponding direct current impulses.

30 Fig. 3 shows a side elevation of a modification of the circuit controller shown in Fig. 2, the modification consisting of tapering the member 18 so that its ends will be of different weights and therefore have different vibrating characteristics so that the 35 ends will vibrate out of phase.

Fig. 4 shows a receptacle 16 containing metallic cup-shaped members 30, 30 having insulated inserts or portions 31, 31 suitably 40 fixed to the leading-in terminals 17, 17. In the arrangement shown in this figure, the leading-in terminals are normally conductively discontinuous due to the insulated portions 31, 31, so that if a local circuit were 45 connected thereto, it would be normally open. The loose contact member shown in this figure consists of two metallic weights 40, 40, suitably joined by a metallic rod 43. For supporting the loose contact member, 50 metallic pins 3, 3 are provided. In order to insure that upon agitation the loose contact element will maintain the local circuit closed, it is desirable that a very small amount of clearance should be provided between the pins 3 and the uppermost inside 55 walls of the cups 30.

Fig. 5 shows an arrangement where the leading-in terminals 17, 17 are provided with metallic cup-shaped members 30, 30 having insulating discs 32, 32 and insulated portions 70, 70. The loose contact member 60 engaging the terminals 17, 17 is made up of dissimilar metallic weights or masses 40, 41 joined by a flexible metallic member or rod 43, and provided with pins suitably

fixed thereto to engage the members 30, 30. The purpose of the discs 32, 32 is to guard against circuit closure on end thrusts during agitation of the loose contact member. By providing the insulated portions 70, 70 the 70 contacting surface for the pins 3, 3 is restricted. A circuit controller constructed in this manner provides normally a closed secondary or local circuit. By providing a flexible member 43 for joining the weights 40, 75 41, a better control of the local circuit is obtained since the weights 40, 41 have a greater tendency to vibrate out of phase than when the rod 43 is rigid.

Fig. 6 shows an arrangement wherein the 80 leading-in terminals 17, 17 support and engage with a loose contact member comprising two dissimilar cup-shaped members 40, 41 and a flexible metallic member 43 for joining the weights. Insulating discs 32, 32 are provided for the members 40 and 41 and are for the purpose of avoiding circuit closure during vibration of the loose contact member due to end thrust.

Fig. 7 shows an arrangement wherein the 90 loose contact member is made up of two dissimilar spherical or ball-shaped masses 50, 60, having bored cavities 53, 53 to engage the leading-in terminals 17, 17, and having insulating discs 32, 32 to guard against circuit closure due to end thrusts on agitation. The masses 50, 60 are joined by flexible metallic member 51. The clearance between the top of the mass 60 and the inner surface 100 of the upper wall of the receptacle 16 is less than the clearance between the lower edges 105 of the leading-in terminals 17, 17 and the lower edges of the cavity 53 in the mass 60 so as to insure disconnection of the terminals 17, 17 during agitation of the loose contact 110 member. With this arrangement, the local circuit would be normally closed.

Fig. 8 shows an arrangement wherein the leading-in terminals 17, 17 have suitably fixed thereto metallic members 55, 55, against 115 which two apertured insulating members 59, 59 which tightly fit into the receptacle 16, rest. The members 59, 59 are provided with apertures 54, 54, through which a flexible metallic member or rod 58 extends so as to 120 engage the metallic members 55, 55. Suitably fixed to the rod 58 are dissimilar spherical masses 50, 60. In this arrangement the terminals 17, 17 are normally electrically continuous.

Fig. 9 shows a modification of the circuit controller wherein the receptacle 16 consists of a tubular glass member having its ends closed by means of insulating members 81, 81. Wax or any other suitable material 125 may be used for sealing the tube after the members 81, 81 are in place. The loose contact member shown herein consists of two dissimilar weights or masses 40 and 41 of metallic material, suitably bored to engage 130

the leading-in terminals 17, 17 and joined by a flexible metallic rod 43, and provided with insulating discs 32, 32 so as to guard against circuit closure on end thrusts during agitation. In this arrangement the terminals 17, 17 are normally continuous.

Fig. 10 shows two receptacles mounted in a socket 13.

Fig. 11 shows a plan view of Fig. 10 with a normally closed circuit including relay 34 and a normally open circuit including relay 96. A single vibrating element may thus control a plurality of circuits. Instead of a direct current source B an alternating current source may be used for all or a part only of the secondary circuits.

Referring now to Fig. 1, a more detailed description of the operation of the relay will be given. There is illustrated schematically in Fig. 1, a circuit arrangement in which the switching device of this invention is useful. Connected to the windings of the switching device is a first circuit having conductors 20, 20. By means of any suitable switch such as 33 and an impulse sender 36, alternating current from a source 35 may be interruptedly applied to the conductors 20, 20 to cause trains of vibrations to be set up in the diaphragm 10. Suitably fixed to the diaphragm 10 is the receptacle 16 containing the circuit controller for the second circuit. This second circuit is shown as containing a direct current source B, two serially connected contacts 25, 25 (shown in Fig. 2) and a winding 34 of a relay. The relay may control any desired circuit (not shown). With the arrangement shown in Fig. 8, current normally flows in the local circuit to energize relay 34. Although the source B in the second circuit is shown as a direct current source, it is obvious that a source of periodically varying current could be employed. As soon as the diaphragm begins to vibrate in response to the alternating current in the first circuit, current in the second circuit will cease to flow and relay 34 will release due to the opening of the local circuit at contacts 25, 25. When the alternating current is cut off from the first circuit the loose contact member 18 will resume its normal position due to the action of gravity resulting in a closure of the second circuit. It will be obvious that by using a circuit controller as shown in Fig. 4, the second circuit will be normally open instead of normally closed.

It will be understood that the diaphragm 10 may be mechanically tuned in any well known manner.

What is claimed is:

1. In a switching device, the combination of a permanent magnet, a winding associated with said magnet, a diaphragm operating in response to the flow of alternating current through said winding, a sealed recepta-

cle mounted on said diaphragm, leading-in terminals for said receptacle, members supported by said terminals, insulated portions thereof, and a member contained in said receptacle loosely engaging said terminals, said insulated portions preventing electrical connection between said members during a portion of each excursion of said diaphragm.

2. In a switching device, the combination of a magnet, a winding associated with said magnet, and a diaphragm operating in response to the flow of alternating current through said winding, with a sealed receptacle mounted on said diaphragm, leading-in terminals for said receptacle, metallic members supported by said terminals, insulated portions therefor, a circuit and a member contained in said receptacle loosely engaging said terminals for controlling said circuit, said insulated portions preventing electrical connection between one of said first members and said second member during portions of the excursions of said diaphragm.

3. The combination with a vibratory element, of an electric circuit, and a circuit controller for said circuit actuated by said vibratory element, said circuit controller comprising a loose contact member consisting of a plurality of dissimilar weights joined by a rod.

4. The combination with a vibratory element, of an electric circuit and a circuit controller for said circuit actuated by said vibratory element, said circuit controller comprising a loose contact member consisting of a plurality of dissimilar weights joined by a flexible member.

5. The combination with a vibratory element, of an electric circuit and a circuit controller actuated by said vibratory element, said circuit controller comprising a loose contact member consisting of a plurality of dissimilar weights joined by a flexible member of electric current conducting material.

6. The combination with a vibratory element, of a sealed receptacle mounted on said element, a loose contact member comprising a plurality of dissimilar weights joined by an electric current conducting member, mounted in said receptacle, and a circuit controlled by said member.

7. The combination with a vibratory element, of a sealed receptacle mounted on said element, a loose contact member comprising a plurality of dissimilar weights joined by an electric current conducting member, mounted in said receptacle, and a circuit controlled by said member whereby the normal condition of the circuit with respect to continuity is altered and such alteration is maintained during the vibration of the vibratory element.

8. A vibrating member, a circuit terminal, a member loosely engaging the terminal and

in electrical connection therewith while the vibrating member is at rest, and means for preventing the electrical connection between the loosely engaged member and the terminal during a portion of each excursion of the vibrating member.

9. A vibrating member and a plurality

of loose contact devices controlled thereby, each said device being constructed and arranged to respond to different types of vibration of said vibrating member.

In witness whereof, I hereby subscribe my name this 29th day of April, A. D. 1922.

HENRY W. O'NEILL.
